MACHINE FOR PRECISION FINISHING OF PARTS BY CONTROLLED VIBRATION

William E. Brandt, Red Lion, Pa., assignor to Lord
Chemical Corporation, York, Pa., a corporation of
Pennsylvania

Application May 8, 1958, Serial No. 50,807

Term of patent 14 years

(Cl. D55—1)

Fig. 1 is a perspective view of a machine for precision finishing of parts by controlled vibration embodying my new design;

Fig. 2 is a top plan view;

Fig. 3 is a rear view; and

Fig. 4 is an end view showing my new design.

I claim:

The ornamental design for a machine for precision finishing of parts by controlled vibration, as shown.
